METHOD AND APPARATUS FOR HANDLING CONTINUOUS FILAMENTARY MATERIAL

Harry J. Hoag, Jr., San Jose, and John R. Meidinger, Palo Alto, Calif., assignors to Owens-Corning Fiberglas Corporation, a corporation of Delaware

Filed Oct. 31, 1960, Ser. No. 66,093
11 Claims. (Cl. 28—64)

This invention relates to handling continuous filamentary material in strand, yarn, or like form. More particularly, the invention relates to a method and apparatus for the supervised advancement of continuous filamentary material in the direction of its length from a supply thereof to a station where the material is further processed, or is incorporated in a product being formed.

The term continuous filamentary material as used throughout this specification and in the appended claims is intended to include individual fibers, multi-filament strands, slivers, rovings, and other continuous flexible textile forms.

In processes wherein continuous filamentary material is continuously withdrawn from a supply and serially advanced by the application of a tractive force thereto to a station for further processing, a variety of problems are encountered that are detrimental to the normal course of the operation, and which frequently cause serious defects in the product being formed from the filamentary material. For example, one of the major problems is that of a "hang-up" or anchoring of the filamentary material, either within the supply or along the path of its advancement. Such occurrences generally result in a complete stoppage in the advancement of the filamentary material, or in a reduction in the rate of advancement of the filamentary material below the rate necessary for the successful operation of the process consuming it.

Other serious problems, often attributable to a "hang-up," are breakage of the filamentary material within the supply, and disruption of the material from the pattern in which it has been incorporated in the product being formed. In this connection, breaking of the filamentary material within the supply results in a considerable loss of time in locating the broken end to restart the advancement process.

Another problem of some magnitude is that of snarls or projecting entanglements occurring along the length of the filamentary material which may cause a "hang-up," or a defect in the product being formed.

It is, therefore, the general object of this invention to provide a novel method and apparatus for the supervised advancement of continuous filamentary material from a supply in a manner obviating the aforementioned problems.

More specifically, it is an object of this invention to provide a method and means for the continuous supervised advancement of filamentary material from a supply thereof, in a manner wherein there is an immediate severance of the filamentary material in the event of a stoppage or of a reduction in the rate of advancement of the filamentary material below a rate that has been predeterminedly established for the successful operation of a process.

A further object of this invention is to provide a method and apparatus which will provide a free end of the filamentary material available for immediate restitution of the processing operation when severing of the filamentary material has become necessary.

A still further object of this invention is to provide a method and apparatus which will prevent breaks in

2

the filamentary material from occurring in the convolutions of the supply.

A still further object of this invention is to provide method and means for sensing the surface of advancing filamentary material for snarls and entanglements being carried along thereon and preventing the advancement of such snarled and entangled material in the event of such occurrences.

Another object of this invention resides in the provision of a method and apparatus for the supervised delivery of continuous filamentary material for incorporation in a mat type product being continuously formed, in a manner whereby disruption or displacement of the filamentary material from the pattern in which it is incorporated in the mat is substantially prevented.

For this accomplishment of the foregoing objects, in accordance with this invention the filamentary material is continuously withdrawn from a supply and serially advanced lengthwise along a predetermined path and delivered to a station for further processing by the application of a tractive force thereto. In successive zones along this path, in advance of the point of application of the tractive force, the surface of continuous filamentary material is first sensed for snarls or entanglements occurring thereon, and then enveloped with a concentration of heat at a temperature sufficient to sever the filamentary material in the event of a stoppage or reduction in the rate of delivery of the material below a predetermined rate.

The foregoing objects of the invention and other objects and advantages which hereinafter appear may be fully understood from a study of the following detailed description taken in connection with the accompanying drawing which is illustrative of a preferred embodiment of the invention, it being understood, however, that the invention is not restricted to a strict conformity with the showing in the drawing but may be changed and modified as long as the changes make no material departure from the salient features of the invention as expressed in the appended claims.

In the drawings:

FIGURE 1 is a side-elevational view in perspective, partially broken away and partially in section, illustrating the invention in conjunction with the formation of a continuous strand reinforced mat;

FIGURE 2 is an enlarged view, in perspective, with parts broken away of portions of the apparatus shown in FIGURE 1, and showing with greater particularity the supervised advancement of a length of continuous filamentary material in accordance with the practice of the present invention; and

FIGURE 3 is an enlarged plan view of a portion of the mechanism for sensing the surface of the filamentary material and guiding it in relation to the severance means.

To provide a better understanding of the invention, it is hereinafter shown and described in conjunction with a process for the formation of a fibrous mat reinforced with continuous filamentary material. Processes of this nature are not amenable to a start-stop operation. This is a particular disadvantage when one or more individual lengths of the continuous filamentary material suffer a stoppage or severe reduction in the rate of its delivery. Such conditions if not immediately relieved impart severe defects in the mat being formed. As will be apparent in the following description the practice of this invention obviates such difficulties. Corresponding advantages are achieved in the fabrication of other textile products incorporating continuous filamentary material.

In the embodiment of the invention illustrated in FIG-

URE 1 molten glass 10 is continuously issued in the form of molten streams 11 from a plurality of outlets 12 provided in the bottom of a feeder 13. The streams 11 are engaged by high velocity gaseous blasts issuing from a blower 14. The blasts attenuate the molten streams 11 into a multiplicity of fine fibers 15 which pass downwardly into a collection hood 16.

Centrally disposed within the hood 16 is a shield or divider 17 of tentlike configuration with its apex located in the upper portion of the hood 16 beneath the hood opening. The divider 17 serves to separate the downwardly moving discontinuous fibers into two groups and provides a shielded zone above a foraminous endless conveyor 18 traveling beneath the hood 16 for the incorporation of continuous filamentary material 22 with the discontinuous fibers 15 being collected theron.

As the conveyor 18 travels beneath the hood 16 the first group of the discontinuous fibers 15 are interfeltingly layered thereon in a random distribution. A plurality of lengths of continuous filamentary material are then randomly distributed thereover in the zone beneath the hood divider 17. As this fibrous mass is moved forwardly by the conveyor into the hood zone beyond the divider 17 the second group of discontinuous fibers is randomly applied thereon.

Deposition of the discontinuous fibers 15 and the continuous filamentary material on the conveyor 18 is facilitated by suction or subatmospheric pressure produced in chamber 19 disposed beneath the upper section of the conveyor. Duct 20 connects the chamber with suitable negative pressure producing mechanism (not shown).

Upon passage out of the hood area the reinforced mat 21 is continuously advanced to suitable apparatus for further processing and packaging.

Reinforced mats of this type produced in the aforesaid manner are well known in the art, and therefore do not constitute per se a part of this invention. However, in such processes serious difficulties, such as the "hang-ups," stoppages, and snarls previously mentioned, have been experienced in the delivery of the continuous filamentary material to the zone of its application to the mat being formed. These difficulties have made the supervised advancement of the continuous filamentary material in accordance with the practice of this invention invaluable.

The continuous filamentary material to be incorporated as a reinforcement in the mat 21 may be, for example, a plurality of continuous glass filaments in the form of a strand 22.

The number of strands utilized and the pattern of their assemblage in the mat 21 may be varied to provide different strength characteristics, however, to avoid serious defects in the end product each strand 22 must be supervisedly delivered. To this end, there is provided a support member 25 located laterally adjacent chamber 19 and exteriorly of the hood 16. Affixed thereto are a plurality of package holders 24, each adapted to hold a supply or package 23 of continuous strand 22.

Above each package 23 is a strand advancing and delivery tube 26 provided with a tubular fitting 27 for the introduction of pressurized air into the bore of the tube. The inlet opening of each tube 26 is positioned above the respective package 23 from which it is to withdraw a strand 22 and deliver it to the mat. Each tube 26 extends through the sidewall of the hood 16 into the shielded zone above the conveyor 18 provided by the divider 17. The outlet opening of each tube 26 is directed toward the conveyor 18 to provide an area coverage of a portion of the surface of the mat layer being advanced thereon. A plurality of such tubes extend as a bank into the zone under the divider 17, the outlet opening of each tube 26 being positioned in spaced relation with the outlet openings of the other tubes to assure full coverage of strands across the width of the conveyor 18.

Suitably supported adjacent and below the inlet opening

of each tube 26 and in the path of advancement of the strand 22 from its package 23, there is provided a strand monitor 29 to first sense the advancing strand for snarls or entanglements projecting therefrom, and secondly to continuously apply a concentration of heat to the strand at a temperature sufficient to sever the strand in the event of a stoppage or reduction in the rate of its advancement below a predetermined rate.

As is more clearly seen in FIGURES 2 and 3, in this embodiment, the strand monitor 29 includes an open flame burner 31, and a strand sensing and guide mechanism 32.

The sensing and guide mechanism 32 is a flat plate having a generally horizontal orientation, with its top surface at one end being affixed to the bottom surface of the block of the burner 31, and having diverging arms 33 and 34 projecting from the side of the plate near the other end thereof. The inner side edges of the arms 33 and 34 are joined by an intermediate arced portion 35 above which a spiral guide coil 37 is located in centered relation. The coil 37 is secured to the plate by arm 36 extending from the coil being fastened to the plate by a retaining clip 38 and screw 39. The coil 37 is centered over the arced portion 35 of the plate. The coil 37 is spiraled vertically with its first turn of largest dimension being smaller than the arced portion 35 of the plate by an amount sufficient to allow free circular entry of the strand into the center opening of the spiral coil 37. The coil 37 is spiraled in the direction of lateral movement imparted to the strand 22 in unwinding it from its package 23. The center opening of the spiral coil 37 is made sufficiently large to allow free axial movement of unsnarled portions of a strand therethrough, but is sufficiently small so that the coil 37 will restrict and halt the passage of large snarled and entangled portions of a strand.

In the burner 31, a hollow, diverging wall flame tunnel 40 is supplied with a metered mixture of gas and air through a pipe 30 adapted to be connected with a suitable supply. The circular face 41 of the tunnel 40 contains a slot 42 of dimension slightly greater than that of the strand 22. The slot 42 is aligned with the center opening in the coil 37 therebelow. The gas-air mixture ignites within the tunnel 40 and projects as an open flame 43 beyond the face 41 to completely envelop the strand 22.

In operation, the end of a strand 22 is withdrawn from its respective supply 23 and threaded through the inlet opening of its associated tube 26. Air from a suitable supply is continuously admitted under pressure through the fitting 27 into the bore of the tube 26. The air creates a zone of reduced pressure at the inlet opening of the tube 26 thereby facilitating threading. The advancing air surrounds the strand applying an impositive force thereto. This force acts to continuously withdraw the strand 22 from its package 23, advance it through the tube 26, and eject it through the tube outlet over the conveyor 18. By regulation of the supply of air the desired rate of advancement of the strand is established.

The strand thus delivered to the conveyor is haphazardly deposited in a random pattern to cover a portion of the layer of discontinuous fibers. The adjacently spaced tubes each similarly deliver a strand. The spacing of the tubes is such that there is a degree of zonal overlap of the strands on the moving conveyor 18 from immediately adjacent tubes. This zonal overlapping distribution reduces the possibility of the formation of a weakened area in the mat during the short period when a strand is not fed to a particular zone due to the severance of the strand occasioned by a restriction on its advancement. Severance of a strand in the manner of this invention provides a "free end" conveniently available for quickly restarting the strand delivery operation.

After the strand 22 has been threaded through the inlet opening of its associated tube 26 and the tractive force for its advancement applied thereto, the strand path in relation to the monitor 29 is established. This

is essentially a self-threading process. As the strand 22 is withdrawn from its package 23 it follows a laterally circular upward path. The opening between the projecting arms 33 and 34 of the guide mechanism 32 is interceptingly located in the path of movement of the strand. Upon contacting the interior sides of these arms, and guided thereby, the strand passes under the impetus of its lateral movement into the path defined by the arced portion 35 of the plate and the side of the spiral coil 37, and progresses into the center opening of the coil 37. At the same time that the strand 22 moves into the center opening of the coil 37, it also becomes engaged in the slot 42 on the lower edge of the face 41 of the flame tunnel 40 since the slot 42 is aligned with the center opening in the coil. At times the strand will momentarily ride on the lower portion of the face 41 until it "finds" the slot 42. In this connection, the face 41 is angularly oriented with respect to the path of the strand 22, and the strand generally does not contact the upper portion of the face 41.

As the strand is advanced through the coil 37 and the slot 42, any snarls and entanglements projecting from its surface result in its movement being halted or restricted by the coil 37 and/or slot 42 to a degree sufficient to effect a severance of the strand 22 by the flame 43. In such event the severed end in advance of the slot progresses through the delivery tube 26, and the snarled end is conveniently located for clipping and rethreading in its tube 26. By its engagement in the coil 37 and in the slot 42, the strand 22 is guided and maintained in its path through the open flame 43.

The continuous application of the flame 43 to the strand has been found to be of value in discharging static charges from strand of a type, such as glass, which tend to accumulate such charges during their handling. Such discharge is effected by the ionizing character of the flame.

In normal operation the advancement of the continuous strand 22 from its supply package 23 to the zone of its incorporation with the layer of discontinuous fibers on the moving conveyor 18 is continuous, and severing of the strand by the flame 43 only occurs when normal advancement is interrupted, for example, by a "hang-up" or anchoring thereof.

In the event of such interruption or stoppage, if the strand 22 were not monitored, severe defects would be imparted to the mat since a pull would be exerted on that part of the strand already incorporated in the discontinuous fibers carried along on the moving conveyor. Such pulls effect a dislodgement of the strand from the pattern in which it has been incorporated in the mat, and also disrupt or dislodge the adjacent discontinuous fibers, forming a blemish or strength defect in the mat. In the production of thin mats such pulls generally result in a dislodgement of strand and fiber sufficient to form a hole or vacant area in the mat. Further, the dislodged strand and fiber fold back on themselves, creating an area of increased thickness adjacent the vacant area, thus portions of the mat formed have to be scrapped and as such mats are often formed in 56" and 72" widths considerable material is wasted.

In view of the severity of these problems caused by such a pull being exerted on the strand, the necessity for immediate remedial action is apparent. As previously referred to, this action is provided by the continuous application of the concentration of heat to the strand being advanced at a temperature sufficient to sever the strand when it is moved at a rate less than a predetermined rate.

The temperature of the severing zone is adjusted in accordance with the rate at which the strand is to be advanced, the length of the heated zone, and the character and thickness of the strand. By way of example, flexible glass strands of dimensions in the range available

for commercial use moving at a rate of 2000' per minute can be successfully monitored by a 1" diameter flame at a temperature in the range of 2800° to 3000° F. Further, by way of example, the burner can be made to effect a severance of such a strand when it moves at a rate slower than 250' per minute, but it will be recognized in view of the present description that the predetermined rate below which severance occurs can be modified by adjustment of the above-mentioned interrelated variables for establishment of the required concentration of heat.

The strand monitor of the invention affords many advantages in that there are no moving parts, it is compact, readily adjustable, and practically maintenance free. Further, it prevents breakages due to anchoring of the strand in the package, as the strand will be severed before sufficient force is applied thereto to break it in the package.

It is readily apparent that the supervised advancement of continuous filamentary material in accordance with the method and apparatus of this invention may be utilized in processes other than that described. For example, the method and apparatus of this invention may be employed to form a continuous strand mat by directing a plurality of tubes each feeding an individual strand to a moving collection surface for assemblage of a mat completely made up of continuous strand material.

Various other modifications may be made in the invention within the spirit and scope of the appended claims to meet diverse requirements.

We claim:

1. A method for the supervised advancement of a continuous length of filamentary material comprising linearly advancing a continuous length of filamentary material from a supply along a given path, concentrating heat in a short zone along the length of the path of advancement of said material, and maintaining the concentration of heat at a temperature sufficient to sharply sever the material within a short distance of movement when the material is advanced at a rate less than a predetermined rate.

2. A method for the supervised advancement of a continuous length of filamentary material comprising continually withdrawing said material from a supply and feeding it in the direction of its length along a given path by the application of a tractive force thereto, and enveloping said material between the zone of application of the tractive force and the supply with a narrow band of open flame at a temperature sufficient to sever said filamentary material when the rate of feed of said material is less than a predetermined rate.

3. A method for the supervised advancement of a continuous length of filamentary material from a supply thereof comprising continually withdrawing said material from a supply and advancing it lengthwise along a given path by the application of a pneumatic force thereto, and enveloping said filamentary material in an open flame of relatively small dimension in a zone between the region of application of the tractive force and the supply, said open flame being at a temperature sufficient to sever the strand when the rate of advancement of the filamentary material is less than a predetermined rate.

4. A method for the supervised advancement of a continuous length of filamentary material from a supply comprising continually withdrawing said material from a supply and advancing it in the direction of its length along a given path by the application of a tractive force thereto, engaging said material between the zone of application of the tractive force and the supply with a concentration of heat in a short zone along the path of advancement of the filamentary material at a temperature sufficient to sever said filamentary material when the rate of advancement of said material is less than a predetermined rate, and passing said filamentary material through a surface sensing system in advance of its engagement by said concentration of heat, said system operable to stop the

advancement of the filamentary material in the event of snarls and entanglements being carried along in projecting relation with the surface of said filamentary material.

5. A method for the supervised advancement of a continuous length of filamentary material comprising continually withdrawing said material from a supply and advancing it in the direction of its length along a given path by the application of a tractive force thereto, enveloping said material in a zone between the region of application of the tractive force and the supply with an open flame at a temperature sufficient to sever the filamentary material when the rate of advancement of the material is less than a predetermined rate, sensing the surface of the filamentary material in advance of its introduction into the open flame to detect irregularities in dimensional linearity such as snarls and entanglements, and restraining the advancement of said filamentary material upon detection of such an irregularity whereupon said filamentary material is severed by said open flame.

6. A method for the supervised advancement of a continuous length of filamentary material from a supply comprising continually withdrawing said filamentary material from a supply and advancing it in the direction of its length along a given path by the application of a pneumatic force in impositive engaging advancing relation therewith, enveloping said material between the zone of application of said force and said supply with an open flame in a short zone along the path of advancement of the filamentary material at a temperature sufficient to sever the filamentary material when the rate of advancement of said material is less than a predetermined rate, sensing the surface of the filamentary material in advance of its introduction into the open flame to detect irregularities in dimensional linearity such as snarls and entanglements, and restraining the advancement of said filamentary material upon detection of such an irregularity whereupon said filamentary material is severed by said flame.

7. In a process for forming on a moving collection surface a fibrous mat incorporating continuous length filamentary material, the steps of continually withdrawing said filamentary material from a supply and feeding it in a direction of its length along a given path by the application of a tractive force thereto in a zone spaced from said supply and adjacent a moving collection surface, serially depositing said material on said collection surface while preserving the continuity thereof with said supply, and enveloping said filamentary material in a zone of relatively short length adjacent the zone of application of said tractive force with a concentration of heat at a temperature sufficient to sever said filamentary material when the rate of feed of said material is less than a predetermined rate.

8. In a process for forming a fibrous mat incorporating continuous length filamentary material, the steps of continually withdrawing a plurality of lengths of filamentary material each from a preformed supply thereof, continually linearly advancing each of said lengths by applying a pneumatic force thereto in a zone spaced from said supply and adjacent a foraminous moving collection surface, serially depositing each of said lengths on said surface while preserving the continuity of each of said lengths between said surface and its supply, and enveloping each of said lengths of said filamentary material in a zone adjacent the zone of application of the pneumatic force with an open flame at a temperature sufficient to sever said lengths when the rate of feed of said lengths is less than a predetermined rate.

9. In a process for forming on a moving collection surface a fibrous mat incorporating continuous length filamentary material, the steps of continually withdrawing and linearly advancing a plurality of continuous lengths of filamentary material from the respective supplies thereof by applying an impositive force in the form of a gaseous blast in surrounding relation with each of said lengths, conveying each of said lengths by means of said blast to a foraminous moving collection surface, establishing a negative pressure zone under said collection surface, depositing said lengths on said surface while preserving the continuity of said lengths with their respective supplies, enveloping each of said lengths in a given zone between the zone of application of said blast and its respective supply with an open flame individual to such length and at a temperature sufficient to sever such length when it is advanced at a rate less than a predetermined rate, sensing the surface of each of said lengths of filamentary material in advance of its introduction into the zone of flame envelopment to detect irregularities in dimensional linearity such as snarls and entanglements, and restraining the advancement of any of said lengths upon the detection of such irregularity on its surface whereupon such length is severed by said concentration of heat.

10. Apparatus for the supervised advancement of a continuous length of filamentary material comprising a supply of said filamentary material, tractive means spaced from said supply for continuously withdrawing and advancing said material therefrom, and open flame producing means located in advance of said tractive means and positioned to continuously apply a concentration of heat across a short length of the path of travel of said filamentary material at a temperature sufficient to sever said material when it is advanced at a rate less than a predetermined rate.

11. Apparatus for the supervised advancement of a continuous length of filamentary material comprising a supply of said filamentary material, pneumatic means spaced from said supply for continuously withdrawing and advancing said material therefrom, flame producing means located in advance of said pneumatic means and positioned to continuously apply a concentration of heat to said filamentary material in a short zone along the path of advancement of the filamentary material at a temperature sufficient to sever said material when it is advanced at a rate less than a predetermined rate, and a spiral coil positioned in the path of advancement of said material in advance of said flame producing means to restrain the movement of said filamentary material when snarls occur thereon.
